UNITED STATES PATENT OFFICE.

ANDREW B. FENNEWALD, OF WESTPHALIA, MISSOURI.

AUTOMATIC HOSE-CO尤PLING.

1,313,805.

Specification of Letters Patent. Patented Aug. 19, 1919.

Application filed December 29, 1917. Serial No. 209,569.

To all whom it may concern:

Be it known that I, ANDREW B. FENNEWALD, a citizen of the United States, residing at Westphalia, in the county of Osage and State of Missouri, have invented new and useful Improvements in Automatic Hose-Couplings, of which the following is a specification.

This invention relates to automatic couplings and especially to couplings for the air or steam hose used on railway cars.

The object is to provide a coupling comprising a reciprocable member having connection with the air line or steam line and mounted beneath the draw head of the car coupler proper in position to effect the automatic connection of the coupling members of the air or steam line when the car couplers are brought into operative position.

20 A further object is to provide for the mounting of a coupler operating in the manner specified, in order that it may have suitable lateral movement and in order that the coupling members proper may also have the necessary movements with reference to the reciprocating portions of the coupling, to permit of the positive and automatic engagement of the contacting plates of the hose coupling when the cars are in process 30 of being coupled together.

A still further object is to provide novel locking means for the contacting plates of the hose coupling members.

Other objects will appear from the following description taken in connection with the accompanying drawings, in which:—

Figure 1 is a top plan view, with parts in section; Fig. 2 is a view in side elevation; Fig. 3 is a horizontal section; Fig. 4 is a rear elevation of an apertured plate provided with an air port, and elements associated with the plate; Fig. 5 is a front elevation of the plate; Fig. 6 is a section on line 6—6 of Fig. 2; Figs. 7 and 8 are diagrammatic views of the plate locking devices; Fig. 9 shows a modification, in top plan and horizontal section. (Figs. 4 and 5 although chiefly in elevation, may be regarded as being taken on lines 4—4 and 5—5, respectively of Fig. 3.)

The mounting means for the hose coupling members will first be described, and in this connection I provide a supporting member designated 10 which is pivotally mounted 55 below the usual car coupler, the pivotal connection being shown at 12. This member

constitutes a guide for a tubular air duct 14 which is movable longitudinally within member 10, said air duct 14 being rectangular in cross section if desired and having 60 connection at its inner end with the air hose forming a part of the air brake system. This connection is shown at 15. A coiled spring 16 surrounds connection 15 and normally forces tubular member 14 outwardly, being 65 compressed when the coupling members are brought into engagement upon the approach of the cars toward each other.

The supporting member 18 constituting a rectangular frame embraces the member 10 70 and tube 14 near their adjacent ends and limits the lateral movement of the structure during the coupling operation. A flat spring 20 secured at 21 bears against portion 22 of supporting frame 18 and serves to 75 retain the parts in proper position for effecting the coupling operation. Connected with portion 22' of member 10 is a socket member 23 secured at 24 and having connection with a rod 25 designed to operate the 80 locking members of the coupler in the manner described below.

A tubular member 30 is connected with air duct 14 and may have an opening therein substantially rectangular in cross section for 85 the accommodation of a similarly formed arm 32. Members 30 and 32 are curved to provide for the swinging movement of the contacting plates 35 of the coupler proper, and within member 30 a coiled spring 36 is 90 mounted to permit member 32 to have an inward movement and to cause said member to be forced outwardly when pressure thereon is relieved. This construction provides for movement due to the passage of cars around 95 curves. An engaging member 37 prevents the outward movement of arm 32 beyond a given point.

The plates 35 which contact with each other during the coupling operation and 100 which effect the connection between the sections of the air line, are substantially diamond-shape in elevation and are provided with openings 39 closed by means of valve members 40 mounted at 41. These plates 35 105 are pivotally mounted on the offset end of the member 14 by means of laterally extending ears 35' secured by pin 35". These valve members have projections 42 thereon, said projections on oppositely located valves 110 contacting with each other when the plates 35 are in engagement so that the valves are

forced inwardly to an open position. The ports 39 have connection with air passages 44 which in turn are secured to a short section of hose 45 leading to main air duct 14. 5 This hose connection provides for the movement of the coupling members, as will be readily understood. Each member 35 is provided with lugs or projections 48 which engage oval-shaped recesses 49 in the complementary plates. The projections 42 on valve 40 do not extend outwardly as far as projections 48 and the valves are held closed until the moment when the two plates are locked together. The locking function is 10 effected by means of locking members 50 which are pivotally mounted by means of bolts 51 on portions 52, each projecting from an arm 32. The locking devices 50 are swung into operative or inoperative position by means of levers 53 which in turn are connected at 54 to a slidable member 55 sliding on a vertically located pin 56. This member is shifted vertically on pin 56 by 15 means of an angle lever 57 pivotally secured to connecting bar 25.

When two cars approach each other, the couplers for the air line being in normal or operative position, the plates 35 are first brought together and these plates slide with 20 reference to each other until the projections 48 come into contact with the oblong recesses 49, the locking devices 50 of course being in inoperative position. Spring 16 is compressed owing to the force exerted by 25 the approaching cars and the member 14 is forced inwardly through the sleeve portion 11 of member 10 thereby effecting the movement of connecting rod 25, lever 57, slidable member 55, arm 53 connecting pin 51 and locking device 50. The latter is thereby 30 thrown into operative position engaging the edges of plate 35 carried by the coupler of the approaching car. Hoods 75 serve to 35 guide the points of the contacting plates 35 into position, these hoods being formed with a concave surface as shown.

In Fig. 9 I have shown a modified form in which an air valve 60 is pivoted at 61 within the main air duct 14'. This valve 60 40 closes a port 62 in a partition member 63 and said port 62 communicates with an air passage 64 through the medium of a short hose connection 65.

In Fig. 8 I have shown in side elevation, 45 another form of construction for operating the locking devices, wherein a connecting bar 68 is provided with a slot 69, one end of said slot engaging a pin 70. The opposite end of the bar 68 is provided with a 50 right angled portion 71 for operating member 72 having connection with the locking mechanism already described.

This avoids the use of construction which 55 may interfere with the operation of the regular car coupling.

Slot 25' in rod 25 permits of a certain amount of play and provides for the movement of the car coupling proper without releasing the lock of the hose coupling.

What is claimed, is:

1. In an automatic hose coupling, a mounting device including a plurality of telescoping members, a spring controlling the position of one of said members, an apertured and vertically located plate forming one of the contacting members of the coupler proper, an air duct extending longitudinally through the mounting device and having connection with the aperture of the plate, locking means mounted on the outer side 75 of the apertured plate and arranged to swing into locking positions, and means for operating the locking member upon the reciprocal movement of one of the telescoping members, said means last named including a fixedly mounted element carried by the telescoping member last named, an angle lever one arm of which is provided with a slot engaged by the fixed element, and devices under the control of the other arm of 80 the angle lever for moving the locking member.

2. In an automatic hose coupling, a plurality of telescoping members one of which constitutes an air duct, a spring for controlling the position of one of said members with reference to the other, an apertured plate forming one of the contacting members of the coupler, a valve controlling the passage of air through the aperture of 95 said plate, a locking device pivotally mounted opposite the plate, a slidable member mounted to move vertically at a point adjacent to the plate, means for connecting the locking device and the sliding member, and means for connecting the sliding member with one of the members first mentioned whereby the locking device is operated upon the relative movement of said members first mentioned.

3. In an automatic hose coupling, a plurality of telescoping members one of which constitutes an air duct, a tubular member extending laterally from said duct, an arm resiliently mounted within the tubular member, an apertured plate constituting one of the contacting members of the coupler carried by said arm, a valve controlling the passage of air through the apertured plate, means connecting said plate with the air 100 duct first mentioned, and locking means operated upon the relative movement of the telescoping members, said locking means including a slidable element and pivoted arms, one of which operates the slidable element 105 and the other of which is operated thereby.

4. In a device of the class described, a plurality of apertured plates, valves for controlling the passage of air through the apertures of the plates, air ducts communicat 110

ing with the apertured portions, means for mounting the plates vertically, said means including devices permitting angular movement with reference to a vertical axis, and 5 telescoping devices permitting movement longitudinally of the line of draft between two vehicles, rotatable devices for locking the plates by engagement with the edge portions thereof, and means for simultaneously 10 rotating the locking devices and opening the valves.

5. In a hose coupling, a plurality of tele-

scoping members, an apertured plate pivotally mounted on one of the members, a flexible duct connected with the apertured 15 portion of the plate, an arc-shaped arm connected with one edge of the plate, an arc-shaped tubular member connected with that telescoping member which mounts the plate, and a spring controlling the movement of 20 the arm within the tubular member.

In testimony whereof I affix my signature.

ANDREW B. FENNEWALD.
